UNITED STATES PATENT OFFICE.

STEPHEN H. FARNHAM, OF BROOKLYN, NEW YORK, ASSIGNOR TO REMINGTON TYPE-WRITER COMPANY, OF ILION, NEW YORK, A CORPORATION OF NEW YORK.

TYPEWRITING MACHINE.

Application filed March 16, 1923. Serial No. 625,450.

To all whom it may concern:

Be it known that I, STEPHEN H. FARNHAM, citizen of the United States, and resident of the borough of Brooklyn, city of New York, in the county of Kings and State of New York, have invented certain new and useful Improvements in Type-writing Machines, of which the following is a specification.

10 My invention relates to paper guiding and controlling mechanism for typewriting machines and the general object of the invention is to provide new and improved mechanism of the character specified.
15 More specifically stated, one object of the invention is to provide a paper deflector or guiding device which is controlled by its own key and may be thrown off at will so as to provide an open throat or entrance
20 way for the convenient front feeding of work sheets. Another specific object is to provide a key controlled guiding device which supplements the deflector and assists in properly guiding the work sheets into the
25 open throat. Other objects will hereinafter appear.

To the above ends my invention consists in the features of construction, combinations of devices and arrangements of parts hereinafter described and particularly pointed out in the claims.

In the accompanying drawings,

Figure 1 is a fragmentary top plan view of the carriage of a typewriting machine embodying my invention.

Figure 2 is a fragmentary end view, partly in section, of the parts shown in Fig. 1.

Figure 3 is a view corresponding to Fig 2 but showing parts in different relationships.

Figures 4 and 5 are perspective views of a modified construction.

Referring first to the form of the invention illustrated in Figs. 1-4 inclusive, the traveling carriage partly shown is that of the No. 11 Remington typewriter, and comprises a rectangular frame or truck composed of grooved front and rear bars numbered respectively 1 and 2 and connected by end bars 3 and 4. The grooved bars 1 and 2 cooperate through anti-friction rollers 5 with correspondingly grooved guide rails (not shown) fixed to the machine frame and on which the carriage and the

parts supported by it are adapted to travel from side to side of the machine. Said carriage in addition to the trucks 1-4 further comprises a carriage frame which is mounted on the truck and which includes end bars 6 having a connecting cross bar 7. The connections between the frame 6-7 and the truck are omitted from the drawings, these being of the usual Remington construction. Mounted on the end bars 6 are the axle portions 8 of the rotary platen 9 with the front face whereof the usual printing instrumentalities (not shown) are adapted to co-operate. Contactive with the platen at its under side is a main feed roller comprising sections 10, and there may also be provided terminal rollers 10^a. Said rollers are releasable by devices comprising a releasing rock shaft 11 mounted on the carriage and provided at its left-hand end portion with a release key 12. Automatic releasing devices for the roller 10 operative at predetermined points in the carriage travel are not shown in the drawing but are illustrated in my companion application, Sr. No. 425,499 filed March 16, 1923. The paper guiding and controlling devices of known construction further comprise a paper pressure device or bail adapted to co-operate with the front upper side of the platen. Said bail is mounted from angular brackets 13 which are secured by screws 14 to opposite end portions of the front bar 1 of the carriage truck. Secured to the upright portions of the brackets 13 by headed screws 15 are rearwardly extending plates 16 which are perforated to receive a rod or rock shaft 17 and provide bearings therefor. Said rock shaft is comprised in the pressure device or bail which further includes rearwardly extending arms 18 secured to the end portions of the rock shaft 17 inside the plates 16 and extending rearward towards the platen. The rear end portions of the arms 18 are perforated to provide bearings for a rod or rock shaft 19. The end portions of the shaft 19 are provided with cross pins 20 which project radially outward through slots indicated at 21 in the arms 18, the construction preventing undue displacement of the shaft 19 longitudinally. Frictionally mounted on the shaft 19 are a plurality of pressure rolls 22 which are adjustable to desired positions along said shaft. The middle por-

tion of the shaft 19 may support a comparatively long pressure roller 23 which is disposed between the inner rolls 22. The pressure roll devices 22 and 23 co-operate with 5 the face of the platen above the printing line and are maintained normally pressed operatively thereagainst by draw springs 24, one at each side of the bail. The rear end of each spring is hooked over a screw 10 25 projecting laterally outward from the associate arm 18 near its rear. Said springs 24 extend forward and downward and their forward ends are anchored to screws 26 secured to downward extensions 16^a of the 15 plates 16. While normally maintaining the pressure roll device or bail in operative contact with the platen said springs permit said bail to be swung upward and forward away from the platen on its pivotal axis 17.

20 My invention comprises in the present instance a paper deflector or apron 27 made preferably of sheet metal and curved to conform to the curvature of the platen. Said deflector is arranged at the under side of the platen and is secured by screws 28 to blocks 29 which may bear rotatively on the rock shaft 11, thus adapting the deflector to turn on the axis 13. Arms 30 fixed to the under side of the deflector or plate 27 at its rear and depending therefrom have coiled springs 31 hooked over their notched lower end portions, said springs extending forward and being anchored to the cross bar 7 of the platen frame. Said springs 31 normally maintain the front portion of the deflector plate 27 in spring pressed contactive engagement with the platen or the paper thereon. The front upper edge of said plate 27 is extended upward as close to the printing line as is possible without interfering with the types, and said edge is found useful as a printing line indicator. The springs 31 cause a light pressure of the front upper edge portion of the deflector plate 27 35 against the platen. It will be observed that unlike the usual construction, the plate 27 is mounted and spring pressed independently of the main feed roller 10 and the other paper feed and paper pressure devices. The 40 deflector plate 27 is formed with openings or windows indicated at 32 through which the sections of the feed rollers 10 and 10^a protrude and contactively engage with the platen. Means hereinafter described are employed for at will moving the deflector plate 50 on its pivotal axis 11 away from the platen so as to provide an opening or throat indicated at 33 between the front edge portion of the deflector and the platen.

60 In addition to the guiding device or deflector plate 27, a supplementary guiding device is provided which is designed to facilitate the introduction of paper into the open throat 33 and the front feeding of such 65 paper. Said supplementary guiding device

or deflector contrivance is preferably mounted on the bail member 17-23 and comprises a square rod or rock shaft 34 which is arranged forward of and parallel with the shaft 19. Said rock shaft 34 is provided at its ends with pintles 35 which bear in openings in the bail arms 18. Frictionally mounted on the rock shaft 34 are a plurality, four in the present instance, of paper guiding devices or fingers. Each finger 36 75 is made of sheet metal and is generally triangular in shape, being bent to surround the shaft and so mounted thereon that it may be slid lengthwise to any desired position longitudinally of the platen. One face of the rock shaft 34 may be provided with a scale or other indicia to facilitate the adjustments of guide fingers 36. The guide fingers 36 are normally maintained thrown off or 80 away from the platen, as in Fig. 2 but key controlled means are provided for rocking the shaft 34 and throwing the fingers into co-operative relationship with the platen as illustrated in Fig. 3. Said means may comprise a toothed collar or pinion 37 fitted over and secured to the left-hand end portion of the rock shaft 34 as by screws 37^a. The radial teeth of the pinion 37 constantly mesh with the teeth 38 of a gear sector 39 having a hub portion 40 which bears rotatively on the shaft 17 somewhat to the right of the left-hand arm 18. The sector 39 is formed with elongated slots indicated at 41 which receive the shanks of headed screws 42 that are threaded into a triangular plate 43. Said screws clamp the sectoral plate 39 and the plate 43 together, and co-operate with the slots 41 to afford relative adjustments of the parts 39 and 43. Integral with the plate 43 is a rearwardly extending 100 finger 44 which is adapted to engage with the left-hand end portion of the deflector plate 27, the upper edge of said plate being cut away to the left of the platen to provide a contact face 45. From Fig. 1 it will be seen that the finger 44 is offset leftward so that its up and down plane of movement is to the left and clear of the platen. The plate 43 is of course perforated to fit over and bear on the shaft 17 in line with the perforation in the hub 40, and the two-part device 39, 43 is constantly spring pressed by a coiled spring 46 which is wound around the shaft 17 and has one end hooked under the plate 43. The opposite or inner end portion of said spring fits loosely over the body portion of a collar 47 having a flange 48 which receives said screws 49 whereby the collar is fixed to the shaft 17. The inner 115 end of the spring 46 is bent out to fit into a hole 50 in said flange. By loosening the screws 49, the flanged collar 47-48 may be rotated on the shaft 17 to vary the tension of the spring 46. Normally said spring maintains the member 39, 43 swung up into the 120 130

Fig. 2 position, the downward movement of said member on the axis 17 being determined by a key contrivance next to be described.

- 5 Said contrivance comprises a key for temporarily throwing the guide fingers 36 into place, and also one for holding or locking them in operative position when desired. Means for this purpose comprises a key member or plate 51 which is roughly 10 T-shaped comprising a rearwardly extending arm 52, a forwardly extending arm 53, and a downwardly extending arm 54. The member 51 is pivoted or hung on a headed 15 shoulder screw 55 which is threaded into the outer face of the plate 43 near its upper end, the member 51 thus being movably supported against the outer or left-hand face of said plate. The rear arm 52 is provided 20 with a key or button 56 and the forward arm 53 likewise carries a key or button 57. The downwardly extending arm 54 is formed with a vertically disposed slot 58 enlarged at its upper end to provide a locking 25 notch or shoulder 59, said slot 58 being engaged by a screw 60 projecting laterally from the left-hand arm or crank 18. The lower end of the slot 58 is normally maintained against the shank of the screw 60 30 by the spring 46 and thus limits the upward movement of the two-part member, 39, 43, maintaining said member and the parts carried and controlled by it in the Fig. 2 position.
- 35 When it is desired temporarily to release or throw off the deflector 27 and concurrently to throw on the supplementary deflector composed of the fingers 36, the key 57 may be depressed, thus swinging the 40 member 39, 43 downward and causing the pinion 37 to be turned by the intermeshing sector 39 to rock the shaft 34 and swing the guide fingers first forward and downward and then rearward into co-operative 45 relationship with the platen as in Fig. 3. As the plate 43 swings downward under the key impulse, the finger 44 will swing with it and towards the end of the key stroke will engage with the contact face 50 45, pressing down on and releasing the paper deflector 27, or swinging it away from the platen to the Fig. 3 position. From Fig. 3, it will be observed that the parts are so related that a work sheet may be introduced over the guiding surface provided by the flat inclined faces of the fingers 36 and thence will readily pass downward through the throat 33. It will be understood that the described movement of the 55 deflector or guiding devices 27 and 36 from the Fig. 2 position to that of Fig. 3 is independent of the feed roller 10, and that said feed roller may be in either operative or released position at the time. On releasing the key 57, the parts will be restored

to normal position by the spring 46. Should it be desired to lock the parts in Fig. 3 position so that both hands of the operator may be free to adjust or manipulate the work sheets or for any other purpose, 70 the rearward key 56 may be depressed. This will result in swinging the plates 39 and 43 downward as before and will also tend to turn the locking plate or member 51 with its arm 54 forward on its axis 55, with the result that as soon as the locking notch at the top of the slot 58 is brought opposite the screw 60, the shoulder 59 will swing under the screw and engage with it as in Fig. 3, providing an interlock between 75 the locking plate 51 and the detent or screw 60 to maintain the parts in depressed position. From this position the parts may be released by pressing the key 57 to disengage the locking plate from its detent and 80 permit the restoring spring 46 to return the parts to normal position.

Modifications may be resorted to without departing from the invention. For example, as illustrated in Figs. 4 and 5, the fingers 36 may be replaced by a continuous 85 guide plate or deflector blade 61 which is secured in a slot indicated at 62 formed in a rock shaft 63 which replaces the rock shaft 34 of the first described construction. The rock shaft 63, it will be understood, 90 may be key controlled by the devices comprising the intermeshing gear members 37 and 39 as before described. A side edge guide contrivance designated as a whole by the numeral 64 will be mounted on the shaft 63. Said contrivance comprises a hub 65 formed with a hole 66 to fit over the shaft 63 and having a longitudinal slot 67 to fit over the blade 61. A thumb screw 68, carried by the hub, maintains the contrivance in adjusted positions lengthwise of the shaft 63. Mounted on and carried by the hub 65 is an angular sheet metal side guide 69 having an upturned side portion 70 against which the left-hand side edge of the paper may be guided when the work sheet is front fed downward over the supplemental paper deflector into the throat 33.

It will be observed that by my present invention there is provided in combination with the platen and paper feeding means, a spring pressed paper deflector, such as 27, and key operated means for at will throwing said deflector away from the platen, the construction enabling this to be accomplished at any point in the carriage travel without the said paper feeding means being affected. In other words, the paper feeding means or feed rollers may remain against the platen and yet the keys of the deflector may be actuated to throw the deflector off or separate its front edge portion from the platen. Otherwise stated, the key operated means for releasing the deflector is entirely 115 120 125 130

independent of the release of the feed rollers. It is further to be noted that means are provided which are operative by one key to throw one deflector off and concurrently for bringing the normally inoperative deflector into paper guiding position relatively to the platen, the thrown-off deflector, when thus released, providing a throat or guiding mouth which facilitates the introduction of the paper at the front side of the platen. It is to be understood, of course, that paper may be introduced at the rear of the platen over the deflector 27 and fed forward under the platen in the usual way, the deflector 27 guiding the paper when thus fed and holding it close to the platen at the printing line. Also, the paper bail contrivance embodying the rolls 22-23 may be employed in association with my novel devices to facilitate the guiding and controlling of the work sheets. Thus, for example, in Fig. 3 where the parts are positioned to receive the front-fed sheet *a*, the pressure bail is shown as maintaining the upper or advanced portion of another work sheet *b* against the platen and so that it cannot fall forward and interfere with the proper front feeding or introduction of sheet *a*. After the sheet *a* has been introduced and positioned, the deflector 27 may be thrown on to hold it and guide it as it is fed forward thereafter in the usual way. The bail or pressure device and the guiding device or supplemental deflector have a common support, the latter device being mounted on the bail and thus being supported from the bail support, which in turn is the traveling carriage or carrier comprising in the present instance the truck 1-4 and the platen frame 6, 7. Both deflectors while they may be moved relatively to the platen transversely thereof, yet have a constant relationship with the platen, considered lengthwise thereof, during its traveling movements and whatever its longitudinal position.

In the present case, I am making only claims which are specific to the constructions shown herein as distinguished from my co-pending application filed herewith, Sr. No. 625,499. Broader claims to cover the constructions of both applications have been made in said co-pending application.

What I claim as new and desire to secure by Letters Patent, is:—

55 1. In a typewriting machine, the combination of a platen, a releasable feed roller, a paper deflector, key operated means for releasing said deflector independently of the release of said feed roller, and means for locking said deflector in released position while said feed roller remains in operative position.

60 2. In a typewriting machine, the combination of a platen, a paper deflector normally co-operative therewith, a second paper

deflector normally maintained in inoperative position, the two deflectors having a constant relationship to the platen lengthwise thereof during traveling movements of the platen, and means for moving said first recited deflector away from the platen and concurrently moving said second recited deflector towards the platen, so that the two deflectors approach the ends of their movements together. 75

3. In a typewriting machine, the combination of a platen, a paper deflector normally co-operative therewith, a second paper deflector normally maintained in inoperative position, and means controlled by a single key for throwing said first recited deflector off and for bringing said second recited deflector into paper guiding position relatively to the platen. 80

4. In a typewriting machine, the combination of a platen, a feed roller, releasing means therefor including a release key, a normally operative paper deflector, a second deflector normally maintained in inoperative position, and key controlled means for actuating said deflectors, the actuating key for both deflectors being operative independently of said release key. 90

5. In a typewriting machine, the combination of a platen, a paper deflector partly underlying the platen, a second paper deflector mounted at the front of the platen independently of the first recited deflector, and a single key operated means for concurrently controlling said two deflectors. 95

6. In a typewriting machine, the combination of a platen, a paper pressure device co-operative with the platen at its front side, and a paper guide device at the front of the platen, one of said devices being mounted on the other. 100

7. In a typewriting machine, the combination of a platen, a pressure roll device co-operative with the platen above the printing line, and a paper guide device mounted on said pressure roll device. 110

8. In a typewriting machine, the combination of a platen, a pressure roll device co-operative with the platen above the printing line, said device being pivotally supported so that it may be swung towards and away from the platen, and a paper guide device pivotally supported on said pressure device and movable into and out of effective position independently of said roll device. 115

9. In a typewriting machine, the combination of a platen, a paper bail, and a paper deflector mounted on said bail. 120

10. In a typewriting machine, the combination of a platen, a paper bail, a paper deflector mounted on said bail, and key operated means for moving said deflector into and out of operative position. 125

11. In a typewriting machine, the com- 130

bination of a platen, a paper bail, and a paper deflector mounted on said bail and normally maintained in inoperative position.

5 12. In a typewriting machine, the combination of a platen, a platen carrier, a spring pressed bail pivotally supported on said platen carrier, and a paper deflecting blade pivotally supported on said bail.

10 13. In a typewriting machine, the combination of a platen, a platen carrier, a spring pressed bail pivotally supported on said platen carrier, a paper deflector pivotally supported on said bail, and a key 15 on said bail for moving said deflector into and out of operative position.

14. In a typewriting machine, the combination of a platen, a platen carrier, a spring pressed bail pivotally supported on 20 said platen carrier, a paper deflector pivotally supported on said bail and movable into and out of effective position, and deflector operating devices comprising a locking plate provided with two keys, one of 25 which renders the plate effective as a lock.

15. In a typewriting machine, the combination of a platen, a platen carrier, a spring pressed bail pivotally supported on 30 said platen carrier, paper deflecting fingers pivotally supported on said bail, and a paper feed roller independent of said bail.

16. In a typewriting machine, the combination of a platen, a platen carriage, a spring pressed bail pivotally supported on 35 said platen carriage, a paper deflecting finger pivotally supported on said bail, a paper feed roller independent of said bail, and a paper deflector also mounted on said platen carriage independently of said bail.

40 17. In a typewriting machine, the combination of a platen, a platen carriage, a spring pressed bail pivotally supported on said platen carriage, a paper deflecting finger pivotally supported on said bail, a paper feed roller independent of said bail, and a paper deflector mounted on said platen carriage independently of said bail and one edge of which serves as a line gage.

18. In a typewriting machine, the combination of a platen, a platen carriage, a spring pressed bail pivotally supported on 50 said platen carriage, a paper deflector pivotally supported on said bail, a paper feed roller, and a second paper deflector co-operative with said feed roller to feed and guide the paper at the under side of the platen, said bail co-operating with the platen at its upper side, and said first recited deflector being adapted to co-operate 55 with the platen at its front side.

60 19. In a typewriting machine, the combination of a traveling platen, a pair of paper guides extending substantially throughout the length of the platen and normally 65 maintained in inoperative position, a key,

and connections from said key for moving said guides into operative position at any desired point in the travel of the platen.

20. In a typewriting machine, the combination of a platen, a paper guide normally 70 in inoperative position, a key, and connections from said key for moving said guide into operative position, said connections comprising a rock shaft, a pinion thereon and an intermeshing gear. 75

21. In a typewriting machine, the combination of a platen, a paper deflector normally in inoperative position, a rock shaft, a pinion thereon, an intermeshing gear sector, a second paper deflector normally 80 co-operating with the platen, means connected with said sector for throwing said second deflector away from the platen, and a key on said sector for actuating both defectors. 85

22. In a typewriting machine, the combination of a platen, a paper guide normally held in inoperative position away from the platen, key controlled means for moving said guide into operative position, a second paper guide, and spring means normally 90 maintaining said second guide in engagement with the platen, said key controlled means comprising a device for overcoming said spring means and forcing said second paper guide away from the platen to provide an open throat to facilitate the introduction of work sheets at the front side of 95 the platen.

23. In a typewriting machine, the combination of a platen, a paper guide normally 100 in inoperative position away from the platen, means for moving said guide into operative position comprising a rock shaft, a pinion thereon and an intermeshing gear sector, a second paper guide normally lying 105 close to the platen, and a finger fixed to said sector and adapted to engage with said second guide to force it away from the platen.

24. In a typewriting machine, the combination of a platen, a platen carriage, a paper deflector curved around the under side of the platen and normally disposed to afford the introduction of work sheets at the rear side of the platen, spring means constantly tending 110 to press the front portion of said deflector into contact with the platen, a second deflector mounted on said carriage at the front side of the platen and normally in ineffective position, and key controlled means for overcoming said spring means and separating the front side of first recited deflector from the platen and for concurrently moving said second deflector into effective position at the front upper side of the platen 115 above the first recited deflector. 120

25. In a typewriting machine, the combination of a platen, a paper deflector normally co-operative therewith, a paper bail, a rock shaft on said bail, a second paper deflector mounted on said rock shaft, a key 130

- member, a pivoted plate on which said key member is pivotally mounted, and means connected to said pivoted plate for actuating both of said deflectors.
26. In a typewriting machine, the combination of a platen, a paper deflector normally co-operative therewith, a paper bail, a rock shaft on said bail, a second paper deflector mounted on said rock shaft, a key member, a pivoted plate on which said key member is pivotally mounted, means connected to said pivoted plate for actuating both of said deflectors, said pivoted key member being provided with two keys, one of which is effective to rock it on its individual pivot and to lock said pivoted plate in effective position.

27. In a typewriting machine, the combination of a platen, a paper guiding device, a key member, and operative connections from said key member to said guiding device, said connections comprising a rock shaft to which said guiding device is secured, a pinion on said rock shaft, a gear sector intermeshing with said pinion, a plate on which said key member is mounted, and adjustable connections between said plate and said gear sector. 20 25

Signed at the borough of Manhattan, city of New York, in the county of New York, and State of New York, this 14th day of March, A. D. 1923. 30

STEPHEN H. FARNHAM.
